UNITED STATES PATENT OFFICE

2,326,334

GARMENT HANGER

James D. Coney, Chicago, Ill., assignor to L. A. Young Spring & Wire Corporation, Detroit, Mich.

Application April 8, 1942, Serial No. 438,140

6 Claims. (Cl. 223—88)

This invention relates to improvements in garment hangers.

The main objects of this invention are:

First, to provide an improved garment hanger including a yoke portion, normally of wire, provided with garment supporting arms and a fibrous cover therefor adapted to be assembled therewith with ease and speed, this cover increasing the area of said arms and being also optionally available as a means for holding a garment on the hanger.

Second, to provide a garment hanger cover of very simple construction adapted to be employed to reinforce, increase and widen the garment supporting surface of the arms of the hanger, thereby permitting the use of small gauge wire and avoiding the objectionably sharp creasing of garments disposed thereon, likewise the soiling thereof, and assisting in frictionally maintaining the garments against sliding off the hanger, which cover may be employed if desired to provide a positive grip on the garments preventing accidental displacement from the hanger.

Further objects relating to details and economies of my invention will appear from the description to follow. The invention is defined in the claims.

A structure embodying the features of my invention is illustrated in the accompanying drawings, wherein:

Fig. 1 is a view in side elevation illustrating a garment hanger having associated therewith a cover in accordance with the present invention.

Fig. 2 is an enlarged fragmentary view in section on line 2—2 of Fig. 1 illustrating the relationship of the garment hanger and the parts of the cover therefor in operative position thereon.

Fig. 3 is a fragmentary view similar to Fig. 1 illustrating the hanger with a garment disposed thereon and indicating the manner in which the hanger cover functions to positively hold the garment in its intended position.

Fig. 4 is an enlarged fragmentary view in section on line 4—4 of Fig. 3, and

Fig. 5 illustrates the cover of the present invention in its flat unfolded blank form.

Referring to the drawing the reference numeral 1 designates a garment hanger of the type shown in my Patent No. 2,260,607 issued October 28, 1941, including a suspending hook 2 attached by a shank 21 to a wire yoke providing downwardly diverging garment supporting arms 3 between which a tubular trouser or skirt supporting strut 4 of fibrous material is disposed.

The reference numeral 5 in general designates the cover of my invention, which is fabricated of a suitable grade of fiber board or heavy paper stock, in flat unfolded condition thereof, shown in Fig. 5. This may be described as having laterally diverging arms 6 of substantial width, preferably provided with a light score line 7 extending centrally and longitudinally of the lower side thereof to facilitate bending or partial folding. 10 The arms 6 are integrally connected by a central front body or shield portion 8 adapted to be disposed at the front of the hanger cover immediately in line with the shank 21 of the hanger. The portion 8 has integrally connected thereto a rearwardly extending flap 9 terminating in a tongue 10 of substantial area defined by the light score line 11. The cover likewise has a light score line 12 defining the flap 9 from the forward shield portion 8. An elongated aperture 13 is centrally located in line with the last named score for the reception of the hanger shank. In use the arms are bent downwardly and disposed to overlie the wire arms of the hanger, increasing the garment supporting area thereof, preventing soiling of the garment and thereby tending to frictionally resist displacement of the garment.

It will be noted that the rearwardly extending flap portion 9 is provided with substantially rounded protuberant sides 14 projecting laterally sufficiently to engage and restrain the coacting projecting enlargements 15 on the rear side of the arms 6, when said arms are bent around the hanger yoke to operative position, as illustrated in Fig. 1. The flap 9 thereby serves to hold the arms in operative yoke encircling or covering position. In said operative position the tongue 10 is folded around and under the extensions 15, engaging the rear surface of the front shield portion 8 so as to be effectively restrained against springing outwardly. The foregoing structure provides a hanger cover which may be applied to a hanger, without the use of any securing means such as staples, pins and the like, in a second's time. In applied position it effectively resists inadvertent displacement.

In addition to functioning to hold the parts of the cover against displacement it will be noted that, as clearly illustrated in Figs. 3 and 4, the flap 9 tongue 10 may be employed to positively hold a garment 16 on the hanger. In employing the cover in this manner the flap and tongue are brought rearwardly and over the collar of the garment and the flap is then tucked upwardly underneath the collar, thereby adding still further to

the effectiveness of the cover in holding a garment on the hanger, over and above the frictional effect attributable to the enlarged garment supporting surface of the hanger. The above feature is especially useful when the garments are to be transported on the hanger in a vehicle subject to sway likely to displace the garments and cause objectionable wrinkling.

An embodiment of the invention which incorporates the principles of the invention in a highly desirable manner has been illustrated and described, though I am aware that other embodiments within the intent of the invention will suggest themselves to those skilled in the art. It should be understood that the foregoing terminology is used only descriptively rather than in a limiting sense, and with full intention to include equivalents of the features shown and described, within the scope of the following claims.

Having thus described my invention, what I claim as new and desire to secure by Letters Patent is:

1. In a garment hanger cover of the type described, a fibrous sheet having a pair of divergent arms of substantial width, a front portion of substantial area integral with and disposed between said arms, and a rearwardly foldable flap in alinement with said front portion, said arms having rear extensions thereon and said flap having side enlargements restrainingly engageable with said extensions when the flap is folded rearwardly into operative covering relation to a garment hanger, said arms in operative position thereof covering the arms of the hanger yoke in downwardly extending position on either side thereof, said flap terminating in a foldable tongue upwardly projecting when in operative use and adapted to be tucked beneath said arm extensions and engageable with the rear side of said front portion to prevent displacement of the cover from the hanger, said tongue being likewise adapted to be tucked around and beneath the collar of a garment on said hanger to positively prevent displacement of the garment from the hanger.

2. In a garment hanger cover of the type described, a fibrous sheet having a pair of divergent arms of substantial width, a front portion integral with and disposed between said arms, and a rearwardly foldable flap in alinement with said front portion, said flap being restrainingly engageable with said arms when the flap is folded rearwardly into operative covering relation to a garment hanger, said arms in operative position thereof covering the arms of the hanger yoke in downwardly extending position on either side thereof, said flap terminating in a foldable tongue upwardly projecting when in operative use and engageable with said front portion to prevent displacement of the cover from the hanger.

3. In a garment hanger cover of the type de-

scribed, a fibrous sheet having a pair of divergent arms of substantial width, a front portion of substantial area integral with and disposed between said arms, and a rearwardly foldable flap in alinement with said front portion, said arms having rear extensions thereon and said flap having side enlargements restrainingly engageable with said extensions when the flap is folded rearwardly into operative covering relation to a garment hanger, said arms in operative position thereof covering the arms of the hanger yoke in downwardly extending position on either side thereof, said flap terminating in a foldable tongue upwardly projecting when in operative use and adapted to be tucked beneath said arm extensions and engageable with the rear side of said front portion to prevent displacement of the cover from the hanger.

4. In a garment hanger article of the type described, a fibrous sheet having a body portion of substantial area, a rearwardly extending flap in alinement with said body portion, and means for the reception of the shank of a garment hanger, said flap being foldable rearwardly and terminating in a tongue portion upwardly projecting when in operative use and separated from said flap by a preformed folding line to facilitate flexing said tongue around and beneath the collar of a garment on the hanger to positively prevent displacement of the garment therefrom, the end of said tongue being free to permit said folding operation relative to the garment.

5. The combination with a garment hanger comprising downwardly diverging arms and a suspending hook provided with a shank connected at the apex of said arms, of a cover formed of fibrous sheet material having downwardly diverging covers for said hanger arms and having an opening at the apex thereof to receive said hook shank, said cover having a rear flap portion foldable over a portion of a garment arranged thereon, said flap portion terminating in a tongue upwardly projecting when in operative use and adapted to be tucked upwardly under the collar of a garment so arranged, the end of said tongue being free to permit said folding operation relative to the garment.

6. A cover of fibrous sheet material for a garment hanger having downwardly diverging arms and a suspending hook provided with a shank connected at the apex of said arms, said cover comprising diverging cover members for said hanger arms, and an opening at the apex thereof to receive said hook shank, said cover having a rear flap portion foldable over a portion of a garment arranged thereon, said flap portion terminating in a tongue upwardly projecting when in operative use and adapted to be tucked upwardly under the collar of the garment, the end of said tongue being free to permit said folding operation relative to the garment.

JAMES D. CONEY.
